FOREIGN PATENT DOCUMENTS

EP	1405145	4/2004
WO	03/007088	1/2003

Primary Examiner — Robin V Webster*(74) Attorney, Agent, or Firm* — Paul D. Bianco; Fleit Gibbons Gutman Bongini & Bianco PL(57) **CLAIM**

The ornamental design for a filter with a timestrip, as shown and described.

DESCRIPTION

FIG. 1 is a perspective view of a first embodiment of a filter system with a timestrip according to the present invention; FIG. 2 is a first side view of the filter system of FIG. 1; FIG. 3 is a second side view of the filter system of FIG. 1; FIG. 4 is a front view of the filter system of FIG. 1; FIG. 5 is a back view of the filter system of FIG. 1; FIG. 6 is a top view of the filter system of FIG. 1; FIG. 7 is a bottom view of the filter system of FIG. 1; FIG. 8 is a perspective view of a second embodiment of a filter system with a timestrip according to the present invention; FIG. 9 is a first side view of the filter system of FIG. 8; FIG. 10 is a second side view of the filter system of FIG. 8; FIG. 11 is a front view of the filter system of FIG. 8; FIG. 12 is a back view of the filter system of FIG. 8; FIG. 13 is a top view of the filter system of FIG. 8; and, FIG. 14 is a bottom view of the filter system of FIG. 8. The broken line showing is included for the purpose of illustrating and forms no part of the claimed design.
